UNITED STATES PATENT OFFICE.

GEORGE E. PANCOAST, OF NEW YORK, N. Y.

PRINTING MACHINE.

Application filed January 4, 1922. Serial No. 526,999.

To all whom it may concern:

Be it known that I, GEORGE E. PANCOAST, a citizen of the United States, residing at New York city, county of Kings, and State 5 of New York, have invented certain new and useful Improvements in Printing Machines, fully described and represented in the following specification and the accompanying drawings, forming a part of the same.

- 10 This invention relates to certain improvements in multi-color printing machines. It is the especial object of the invention to provide a construction and arrangement of printing and perfecting mechanisms and a 15 folder for printing and perfecting a plurality of webs in black, in color, or in black and color, the construction including guides and angle bars for so leading the webs from the printing mechanisms to the folder that 20 the webs may go to the folder either side up and the color and black webs may be placed in desired position with each other, and products may be produced having black and color pages arranged in combinations 25 which cannot be produced with previous color press arrangements so far as known to me.

A further object of the invention is to produce a press construction and folder in 30 which these products may be produced on either a right angle folder, that is a folder at the side of the press, or a straight line folder at the end of the press.

With these and other objects not specifically referred to in view, the invention consists in certain novel arrangements and combinations which will be described in detail in connection with the accompanying drawings and the novel features then pointed out 40 in the claims annexed hereto.

In the drawings—

Figure 1 is a diagrammatic side view of a multi-color printing and perfecting mechanism employing three webs and in which 45 there are shown twelve printing couples with the angle bars and web guides showing the run of the three webs for producing special black and color products.

Figure 2 is a diagrammatic end view on 50 a somewhat enlarged scale of the web guides and angle bars showing the web runs of Fig. 1, looking in the direction of arrow 2 of that figure, the product being illustrated as being run to one or more formers arranged 55 at one side of the printing mechanisms.

Figure 3 is a diagrammatic plan view showing the run of one of the webs as led to a side folder.

Figure 4 is a diagrammatic plan view showing a modification of the arrangement 60 shown in Fig. 3 which may be used with a side folder.

Figure 5 is a diagrammatic plan view showing the run one of the webs when a straight line folder is used; and

Figure 6 is a diagram of the pages of the product produced with the three web run shown in Figs. 1 and 2, the color pages being indicated by circles surrounding the 65 page designations.

Referring now to these drawings, an arrangement has been shown which will produce a twenty four page product having one special combination of black and color pages. In the arrangement shown this product is produced from three webs printed from printing and perfecting mechanisms in which the plates are arranged on the cylinders four wide, and in which the color pages are printed in four colors. In this 70 product produced by the arrangement shown, pages 1, 6, 10, 12, 13, 15, 19 and 24 (see Fig. 6) are printed in colors (four colors) and the remaining pages are printed in black. The folded product produced has 75 the two outside pages in color and the two inside pages in color with other color pages between successive three black pages, at both sides of the middle of the product, this product being particularly desired in producing 80 the so-called color section of special newspaper editions, as the Sunday editions. The arrangement for producing this product illustrates the invention, but it will be understood that other special products with 85 special arrangements of the color and black pages may be produced with the mechanism illustrated, and the invention is not to be restricted to the web runs illustrated or the product produced thereby.

In the drawings there is illustrated a twelve unit press, that is, a press comprising twelve printing couples, these couples being arranged as shown in superposed sets of six. These couples are designated generally 1, 2, 3, 4, 5, 6, 7, 8, 9, 10, 11 and 12, and each includes a form cylinder 13 and an impression cylinder 14. A suitable inking mechanism, indicated by the numeral 15, is provided for each couple, this mechanism 90 100 110

being arranged so that it may be moved bodily back from the form cylinders as shown at the left in Fig. 1, so as to leave a clear access to the cylinders for dressing them with the plates. The form and impression cylinders and the inking mechanism are supported in suitable side frames 16, and cross frames 17. At one side of the press are arranged brackets 18 for carrying 10 web rolls indicated at 19, six rolls being illustrated, three of which are active and three of which are spares, the webs from the three active rolls being indicated by W, W', W².

To produce the particular product illustrated, one of these webs is printed and perfected in black and the other two webs are printed on one side in black and on the other side in colors, four colors being printed on these webs in the particular construction illustrated, the web W' being printed and perfected in black and webs W and W² being printed in black and colors.

These three webs are as before stated four pages wide, and after they have been 25 printed and perfected are slit so as to form six webs, each two pages wide. The webs are led from the printing mechanism over suitable guide rolls 20, to the slitters, three such slitters 21, 22 and 23 being indicated in 30 Fig. 1, and after slitting the webs are conducted to the folders.

The present invention provides means whereby these webs may be assembled at the former or folder to produce combinations of 35 black and color pages which could not be obtained with prior arrangements so far as known to me. Generally these means include web guides by which any of the webs may be led to the former either side up, and 40 with the black in any desired relation to the color, whether used with a right angle folder or a folder at the end of the press in line with the web run. These guides include turning bars and guide rolls arranged to 45 turn a web and lead it direct to the folder where the folder is a right angle one, that is, a folder at the side of the press, or lead the web past or beyond the folder or out to one side of its normal path and away from 50 the folder for reversal, and then back to the folder, said web guides also being arranged so that certain of the webs may have a longer path than the others and may be led around outside of other webs for positioning 55 them relatively to the other webs, depending on the particular product desired.

This may be effected in various ways, certain of which are shown in the drawings. In the preferred construction and as illustrated in Figs. 1 to 3, the webs are led for reversal past or beyond a right angle folder over a guide roll and then over a turning bar back to the folder, and this construction will first be described.

60 In this arrangement there is provided a

folder arranged at one side of the press, that is, at right angles to the run of the product through the machine, and this folder may include a pair of superposed formers 25 and 26, to either or both of which the product 70 may run, this construction being illustrated in Fig. 2 guide rolls 26' being provided for effecting this.

The reversing and turning guides include angle bars, one of these angle bars being 75 provided for each of the webs and six such bars being shown marked 27, 28, 29, 30, 31 and 32. These angle bars are made reversible so as to guide the webs in different ways depending on the particular arrangement of 80 color and black pages desired in the final product.

Guide rolls are provided over which the webs may be led past or beyond the folder for reversal, such rolls being marked 33, 34, 35 and 36, 360, 361, one of these rolls being provided for each angle bar. These rolls are preferably mounted so that they may be moved to different positions, as illustrated 90 in dotted lines in Fig. 1.

The guides for each of the webs, therefore, include angle bars and a movable guide roll, this guide roll being movable so that a web may be led to its particular bar from above or below. In the preferred construction and where a right angled former is used, these guides are preferably arranged in offset relation to each other, as shown in Fig. 2, so that the webs next the folder may go to the folder without having to run through or between the webs on the off side of the folder.

The web guides for effecting the objects of the invention will also include other additional guides arranged beyond the guide rolls provided for each of the angle bars so that certain of the webs may be guided around webs going over these rolls and placed in between other webs as desired, and a pair of these rolls marked 400, 401 are shown (see particularly Fig. 1) for effecting this, over which the webs may be directed in either direction, depending on the combination desired.

An explanation of a web run for producing the product shown in Fig. 4 will suffice for an understanding of the invention.

The web W is led over suitable guides 40 to printing couple 4, by which it is printed on one side in black, and is printed on the other side in four colors by printing couples 5, 6, 7 and 8 whence it is led to the slitter 21.

Web W' is led over suitable guides 41 to printing couples 10 and 9, by which the web is printed and perfected in black and then led to the slitter 22.

Web W² is led over suitable guides 42 to couple 3 by which it is printed on one side in black and then to and through couples 2, 130

1, 12 and 11, by which it is printed on the other side in four colors and then led to slitter 23.

In the particular run illustrated, web W is divided by the slitter 21 into webs R' and F'. The web R' has color pages 1 and 24 on one side and black pages 2 and 23 on the other, and the web F' has color pages 6 and 19 on one side and black pages 5 and 20 on the other.

Web W' is slit by the slitter 22 into webs R² and F², and both these webs have black pages on each side, the pages in the particular run illustrated being 3 and 22, 4, 21 on web R², and pages 7, 18 and 8, 17 on web F².

Web W² is divided by the slitter 23 into webs R³ and F³. Web R³ has black pages 9, 16 on one side and color pages 10 and 15 on the other, and web F³ has black pages 11, 14 on one side and color pages 12, 13 on the other.

To produce the particular product illustrated, web R' is run over suitable guides 25 to and around roll 33 past or beyond the folder, then back over angle bar 27 so as to bring the color pages 1, 24 on top. As the next two pages 3, 4, 21, 22 are to be black, one half R² of the black web W', which is 30 black on both sides, is run over the long path over the outer guide roll 400 to and over angle bar 28 and out to the folder, web R² being then positioned between webs R' and F'. As the next two pages 5, 20 are to 35 be black followed by color pages 6, 19, the other half F' of web W is run down over guide rolls 46, and turned over angle bar 29 and led direct to the folder, thus bringing the black pages of this web in the desired relation. As the next pages 7, 18 and 40 8, 17, are to be in black the other half, F² of web W' is run down over guide rolls 47 and turned over angle bar 30 and out to the folder. The next pages 9, 16 being in 45 black and 10, 15 being in color, one half R³ of web W² is led to and turned over bar 31 and then sent direct to the folder while the other half F³ is guided around guide rolls 48 to reversing roll 361 out past or beyond 50 the folder, and then back for reversal over bar 32 and then to the folder.

It will be apparent that by reversing the angle bars and changing the run of the webs so that the black is led in at other 55 points a wide variety of special combinations of black and color may be obtained.

In Figs. 4 and 5 there has been illustrated certain modifications of the arrangement of the bars and rolls by which the same products may be obtained and which under certain circumstances may be employed, Fig. 4 showing a modified run with a right angle folder and Fig. 5 a run with a straight line folder.

66 Referring to Fig. 4, the webs for reversal

are first run over the angle bars and then away from the folder and around the rolls for reversal and then back to the folder. The rolls in this particular instance and the bars would be in the same vertical plane, 70 with the rolls for giving the longer path to the web arranged outside, as shown at the left in the figure.

In Fig. 5 is illustrated a run whereby the desired combinations may be effected with 75 a straight line folder. When this run is employed there will be provided two angle bars 50, 51, for each web or half web, the web turning over angle bar 50 and then to the reversing roll and then back over angle 80 bar 51 and then out to the former.

All the webs may be associated superposed at either of the formers 25, 26, the guide rolls 26' being arranged and provided for effecting this, this arrangement producing the product illustrated in Fig. 4. It will, however, be understood that where certain products, as all black products, for instance, are being produced, part of the webs may be led to one former and part to 90 the other.

While the preferred arrangement of the parts has been illustrated, it will be understood that the invention is not to be restricted to the particular runs shown and described, nor to the particular product produced, but that a wide range of products may be effected and the runs may be arranged in various ways for effecting the production of the desired products. 100

What I claim is:

1. In a printing machine, the combination of a plurality of web perfecting mechanisms capacitated to print a plurality of webs in black or in color, or in black and color, a folder at one side of the perfecting mechanisms, and web guides arranged to turn a web and lead it to the folder, or lead the web past or away from the folder for reversal and then back to the folder, 105 said web guides also being arranged so that certain of the webs may have a longer path than others and may be led around outside other webs for positioning them relatively to the other webs. 115

2. In a printing machine, the combination of a plurality of web perfecting mechanisms capacitated to print a plurality of webs in black or in color, or in black and color, a folder at one side of the perfecting 120 mechanisms, and web guides arranged to turn a web and lead it to the folder, or lead the web past or away from the folder for reversal and then back to the folder, 125 said web guides also being arranged so that certain of the webs may have a longer path than others and may be led around outside other webs for positioning them above, below or in between other webs.

3. In a printing machine, the combina- 130

4
tion of web perfecting mechanisms capacitated to print a plurality of webs in black or in color, or in black and color, a folder at one side of the perfecting mechanisms, 5 slitters for dividing the webs, web guides for each slit web arranged to turn a web and lead it to the folder, or lead the web past or away from the folder for reversal and then back to the folder, and web guides 10 arranged to direct certain of the webs around outside other webs for positioning them relatively to other webs.

4. In a printing machine, the combination of web perfecting mechanisms capacitated to print a plurality of webs in black or in color, or in black and color, a folder at one side of the perfecting mechanisms, 15 slitters for dividing the webs, web guides for each slit web arranged to turn a web and lead it to the folder, or lead the web past or away from the folder for reversal and then back to the folder, and web guides 20 arranged to direct certain of the webs around outside other webs for positioning them above, below, or in between the other webs.

5. In a printing machine, the combination of a plurality of web perfecting mechanisms capacitated to print a plurality of webs in 30 black or in color, or in black and color, a folder, and web guides arranged to lead a web to the folder either side up and so that certain of the webs may have a longer path than others and may be led up or down and 35 around other webs for positioning them in desired relation with other webs above or below them.

6. In a printing machine, the combination of a plurality of web perfecting mechanisms 40 capacitated to print a plurality of webs in black or in color, or in black and color, a folder, slitters for dividing the webs, web guides for each slit web arranged to lead a web to the folder either side up, and 45 web guides arranged to direct certain of the webs around outside other webs for positioning them above, below, or in between the other webs.

7. In a printing machine the combination 50 of a plurality of web perfecting mechanisms capacitated to print a plurality of webs in black or in color, or in black and color, a right angle folder, and web guides arranged to lead a web to the folder either side up 55 and so that certain of the webs may have a longer path than others and may be led around outside other webs for positioning them relatively to other webs.

8. In a printing machine, the combination 60 of a plurality of web perfecting mechanisms capacitated to print a plurality of webs in black or in color, or in black and color, a right angle folder, slitters for dividing the webs, web guides for each slit web arranged

to lead a web to the folder either side up, 65 and web guides arranged to direct certain of the webs around outside other webs for positioning them above, below, or in between other webs.

9. In a printing machine, the combination 70 of a plurality of web perfecting mechanisms capacitated to print a plurality of webs in black or in color, or in black and color, a folder, web guides for each web including a reversible angle bar and a roll arranged to 75 lead a web away from or past the folder and then back over the bar to the folder, or lead the web over the bar direct to the folder, and web guides arranged outside the bars and rolls by which a web may be led around 80 outside other webs for positioning them relatively to other webs.

10. In a printing machine, the combination 85 of a plurality of web perfecting mechanisms capacitated to print a plurality of webs in black or in color, or in black and color, a folder, sets of web guides for each web, each set including a reversible angle bar and a roll arranged to lead a web to the folder, or lead a web away from or past 90 the folder for reversal and then back to the folder, and guide rolls outside the bars and rolls by which a web may be led around outside other webs for positioning them 95 relatively to other webs.

11. In a printing machine the combination 100 of a plurality of web perfecting mechanisms capacitated to print and perfect a plurality of webs, a right angle folder, web guides arranged to turn one or more of the webs and lead such web to the folder, or to lead one or more of the webs past or beyond the plane of the folder for reversal and then back to the folder, and web guides arranged 105 so that one or more of the webs may have a longer path than others and may be led up or down and around other webs for positioning them in desired relation to webs above or below them.

12. A printing machine including in combination three presses capacitated to print three double wide webs in black or in color, or in black and color, a folder at one side of the presses, slitters for each double wide web, an angle bar and roll for each slit web arranged superposed, and guides whereby one of the slit webs may be led up or down to position it in desired relation with the webs above or below it.

13. A printing machine including in combination three presses capacitated to print three double wide webs in black or in color, or in black and color, a folder at one side of the presses, slitters for each double wide web, an angle bar for each slit web, a movable roll for guiding the web under or over a bar, said bars and rolls being arranged 120 superposed and guides whereby one of the 125

webs may be led upon or down to position it in desired relation with the web above or below it.

14. A printing machine including in combination three presses capacitated to print three webs in black or in color or in black and color, a folder at one side of the presses, an angle bar for each web, a removable roll

for guiding the web under or over a bar, said bars and rolls being arranged super- 10 posed, and guides whereby the middle web may be led up or down to position it on either side of a web above or below it.

In testimony whereof, I have hereunto set my hand.

GEORGE E. PANCOAST.
